ATTORNEY

UNITED STATES PATENT OFFICE

JOHN B. BRENNEN, OF ATLANTA, GEORGIA

ATTACHMENT FOR COTTON-CLEANING MACHINES

Application filed March 22, 1929. Serial No. 349,181.

This invention relates to an attachment for a cotton cleaning machine, the general object of the invention being to provide a rock shaft in the top of the cleaner, with beater forming parts depending therefrom, with yieldable means for normally holding the parts in a position with the beater forming parts in a vertical position whereby when the cotton is thrown against said beater parts 10 by the main beater of the machine, the shaft and beater parts will move to a position where the beater parts will be in a diagonal position and then the yieldable means will return the parts to normal position so that the 15 attachment will exert an opening effect on the cotton in addition to that exerted by the main beaters.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is an elevation of a cleaning machine equipped with this invention.

Figure 2 is a vertical sectional view through a portion of the cleaner casing.

Figure 3 is a front view, with parts in section.

In these views, the numeral 1 indicates the cleaner casing in which is located the main beaters 2 carried by the shaft 3, this shaft being driven in any suitable manner.

In carrying out my invention, I place a second shaft 3' in the top of the casing, this shaft being in alignment with the shaft 3 and having its ends suitably journaled in the ends of the casing and said ends of the shaft project from the casing. A plurality of depending beaters 4 is fastened to the shaft 3 within the casing and an arm 5 is connected with each outer end of the shaft. A spring 6 bears against the lower end of each arm 5 and engages a bracket 7 on the exterior part of each end of the casing, these springs acting to hold

the parts with the beaters 4 in depending position.

From the foregoing it will be seen that as the cotton is thrown upwardly by the main beaters, the cotton will strike the beaters 4 and thus cause the beaters to rock the shaft 3 against the action of the springs 6 which engage the arms 5 of the shaft so that said springs are compressed and thus the springs act to return the parts quickly to normal position so that the beaters 4 are subjected to practically a continuous rocking movement. The auxiliary beaters 4 will exert a material opening effect on the cotton thrown against them by the main beaters so that the opening action of the machine is greatly increased.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A cotton cleaning machine comprising a casing, a shaft rotatably mounted in the lower portion of the casing, beaters fixed for rotation with the shaft, a shaft mounted in the end walls of the casing parallel to and above the first mentioned shaft, arms extending downwardly from the last mentioned shaft at the ends thereof, tension springs connected to the lower ends of the arms and to the corresponding end walls of the casing and yieldably holding the arms in a vertical position, and beater members fixed at their upper ends to the last mentioned shaft and extending vertically downwardly therefrom and in vertical planes with respective alternate ones of the beaters upon the first mentioned shaft.

JOHN B. BRENNEN.
